UNITED STATES PATENT OFFICE.

FRANK E. LIVERANCE, JR., OF GRANDVILLE, MICHIGAN.

AUTOMOBILE HOOD LATCH.

Application filed April 26, 1926. Serial No. 104,616.

This invention relates to an automobile hood clamp or latch designed for the purpose of holding doors of a hood over an engine in closed position but being freely disengageable therefrom so as to permit opening when desired. A primary object and purpose of the present invention is to provide an improved latch for the purpose stated which is very simple in construction, 10 economical to manufacture, durable and efficient in service and which may be used to hold the hood door into snug and tight engagement against an abutment against which it bears at its lower edge whereby rattling is obviated. One feature of particular advantage in connection with this latch structure is that its manufacture and assembly is particularly practical, it being impossible to assemble the parts in a wrong manner, and, all of the parts being of simple 20 stampings, there is no necessity for close inspection or watching of the process of manufacture in the factory because of the inability of workmen to make mistakes 25 either in fabricating or assembling the construction. With the above and other objects of the invention in view, the invention consists in the improved hood door latch, understanding of which may be had from the 30 following description taken in connection with the accompanying drawing, in which

Fig. 1 is a fragmentary sectional view of a hood showing the latch, which appears in elevation, connected therewith.

Fig. 2 is a view similar to Fig. 1 showing the latch disconnected from the hood door.

Fig. 3 is an elevation of the structure shown in Fig. 1 looking at the same from the right.

Fig. 4 is an enlarged vertical section 40 through the latch.

Fig. 5 is a view similar to Fig. 1 showing a different form of the latch structure and one wherein the engagement of the same 45 with the hood door is nearer the lower edge, the latch proper being positioned at an angle to the vertical.

Fig. 6 is an elevation of the latching member used in the construction shown in Fig. 5.

Fig. 7 is a view similar to Fig. 1 wherein the latching member may also be used to press the hood door into tight engagement at its lower portion with a fixed abutment, and Fig. 8 is a fragmentary elevation of the

structure shown in Fig. 7 looking at the 55 same from the right, the latch being disengaged and turned to down position.

Like reference characters refer to like parts in the several views of the drawing.

A part of a hood which is to be latched 60 in closed position is indicated at 1, it, when in closed position, coming outside of an abutment 2 which is turned upwardly from a sheet metal covering 3 placed over a suitable fixed support 4, which may be one of the two longitudinally extending side frame members of the vehicle chassis. The construction of the door and the method in which the abutment against which it bears 65 forms no part of the present invention and that shown is for illustrative purposes only.

The latch construction includes a member of sheet metal having a base 5 from which two spaced apart ears 6 extend upwardly. Said base is designed to be rigidly secured 70 adjacent the door and above the frame member 4 by any suitable fastening means such as the bolts shown. Above the member described a substantially cylindrical housing is 75 mounted. The housing is formed of sheet metal pressed into two semi-cylindrical halves 7, bent near its middle point so as to bring the halves together and make a closed upper end to the housing. The edges of the cylindrical section 7 come together at the 80 sides of the housing as indicated at 8 in Fig. 2. Preferably, an opening 9 will be left at each side adjacent the upper end of the housing for facility in manufacturing and also to furnish an opening for the oiling of 85 the spring which is housed within said housing, as will later appear. At each side, portions of the metal are cut away so that the housing at the lower end has slots 10 in each side which extend from the lower end of the 90 housing approximately one third of its height. The metal at the lower of each half of the housing is left flat making the downwardly extending ears 11 which are designed to pass between the ears 6 of the 95 supporting member heretofore described. In practice the metal of the ears 11 will be pressed inwardly to make the embossings 12, each in depth substantially one half the 100 width of the slots 10 so that the same will come together and properly space the ears 11. A pivot pin 13 passes through the ears 105 6 and 11 so that the housing may be mount-

ed for pivotal movement on the supporting member. The axis of the pin 13 is at right angles to the plane of the hood door 1 whereby the housing may be turned in a plane parallel to the plane of the hood door.

Associated with the housing is a latching member of sheet metal having two sides 14 connected at their lower end by a cross bar 15 rounded so that it may turn freely in the slots 10 of the housing in which it is located. This member is made from flat stock and the side bars 14 are at each side of a rectangular opening 16 which is cut in piece from which the member is made, the cross bar 15 being at the lower end of said opening. The upper end of the latching member is formed into an outwardly extending handle or finger engaging part 17 and above the rectangular opening 16 a hook 18 is struck and bent inwardly, it being designed to engage with a fixed keeper 19 secured to the outer side of the hood door 1. A coiled spring 20 is located in the housing between its upper end and the cross bar 15 of the latch member described.

It is evident that with the parts assembled as stated, the tendency of the spring 20 is to force the bar 15 in a downward direction but that by engagement with the handle 17 and pulling upwardly the spring may be compressed and the latching member moved in an upward direction, at least as far as the slots 10 will permit. Accordingly, the latching member may be lifted to a position that the hook 18 will engage with the keeper 19 and when released the spring 20 will move the latching member downwardly so as to cause hook 18 to engage with said keeper 19, spring 20 under compression, exerting a force at all times to move the latching member in a downward direction. The release of the hook 18 from its keeper 19 is accomplished by pulling upwardly on the handle 17 until the hook is disengaged, whereupon the latching member may be turned outwardly to the position shown in Fig. 2, the hood door being released. At the same time, if desired, the housing may be turned about the axis of the pivot 13 so as to move it to a lower position.

In Fig. 5 a slightly different form of the construction is shown, the base 5 having its ends stamped so as to position the ears 6 at an angle to the vertical whereupon the housing member will lie at the same angle to the vertical. The latching member does not have the hook 18, previously described but at each side near its lower end integral hook fingers are struck from the body of the latch member and curved inwardly and downwardly to make the hooks 21 adapted to engage with a keeper 22 close to the lower edge of the hood door 1. The angular position of the latch and the direction of force of the spring by reason of such position

makes a horizontal component of such force have the effect of moving the lower portion of the hood door 1 inwardly against the abutment 2 while the other or vertical component of the force pulls on the door in a downward direction.

In Figs. 7 and 8 the construction shown in Figs. 1 to 4, inclusive, is slightly modified in that each of the side bars 14 of the latching member near their lower ends are formed with forwardly curved sections 23, substantially semi-circular in form, which bear, when the latching member is engaged with its keeper, against a member 24 of leather, rubber or like material attached to the hood door. This causes the door to be pressed inwardly snugly against the abutment 2, as is obvious.

There are many other modifications which may be made. For instance, the hood latch may be turned to a position at right angles to that shown and turn on the pivot toward or away from the hood door, in which case the upper end of the latching member would be supplied with an engaging hook or the like and a handle for manual operation substantially in the plane of the latching member and at the upper end thereof.

The latching member is simply and easily formed from flat bar stock in a punch press. The housing member is likewise the product of punch press operations as is also the base member to which it is pivotally connected. The assembly consists in pulling the ears 11 far enough apart that the spring 20 may be placed in the housing, putting the cross bar 15 of the latch member below the spring, fitting the ears 11 between the ears 6 and inserting and securing the one pivot pin 13. Because of the symmetrical construction there is no possibility of misassembling the housing, latch bar and spring, and in all of the constructions except that shown in Fig. 5, there can be no misassembly of the housing with the supporting base. The construction is thus particularly feasible for quantity production manufacture, no particular care and watchfulness in the factory being needed. In addition it is strong and durable and by reason of the pivotal connection of the housing to the base, the latch may be turned to a lower position, as in Fig. 8, where it is practically out of the way. The invention is defined in the claims appended and is to be considered comprehensive of all forms of structure coming within their scope.

I claim:

1. A hood clamp for motor vehicles and the like comprising a tubular housing having a closed end and slotted at opposite sides, a spring located within the housing, and a latching member formed with an elongated opening lengthwise thereof and with a cross bar at one end, said cross bar passing

- through the housing at the slotted sides thereof, and at its opposite end having means to be manually engaged to draw the cross bar against said spring to compress the same.
2. A hood clamp for motor vehicles and the like comprising a tubular housing having a closed end and longitudinally slotted at opposite sides, a coiled spring located within the housing, a supporting base to which said housing is pivotally connected at the end thereof opposite its closed end, and a substantially rectangular shaped latching member having two sides spaced apart and connected at one end by a cross bar, the opposite end having a handle formed thereon, said cross bar passing through the slots in the sides of said housing between said spring and supporting base.
3. A hood clamp for motor vehicles and the like comprising a tubular housing having one end closed and formed at its opposite end with two parallel ears, said housing being slotted in opposite sides away from said ears, a supporting base to which said ears are pivotally connected, a coiled spring within said housing, and a latching member slidably mounted on said housing having a part passing through said slotted sides of the housing between the end of the spring and said supporting base.
4. A hood clamp for motor vehicles and the like comprising an elongated housing having one end closed and slotted longitudinally at opposite sides, a supporting base to which said housing is pivotally connected, a coiled compression spring located within said housing, a latching member having spaced apart sides connected at one end by a cross bar connected with said housing, said cross bar passing through the slotted sides of the housing and engaging against one end of said spring, a handle at the opposite end of the latching member and hook engaging means carried by said latching member.
5. A hood clamp for motor vehicles comprising a supporting base, a housing pivotally connected to said base at one end, a spring located within said housing, and a latching member slidably and pivotally mounted on said housing, being slidable in one direction to compress said spring and having pivotal movement with respect to said housing about an axis located at right angles to the axis about which the housing has pivotal movement.
6. A hood clamp comprising a supporting base, a tubular housing having oppositely slotted sides pivotally connected at one end to said base, the opposite end of the housing being closed, and a hood latching member pivotally and slidably connected with said housing and having a part passing through the slotted sides of said housing combined with a spring located within said housing against which said part of the latching member engages to compress the spring on movement in one direction.
7. A hood clamp comprising a housing having oppositely slotted sides located lengthwise of the housing, a spring within said housing, and a hood latching member pivotally and slidably mounted on said body and having a part extending through the slotted sides thereof, said latching member including a finger hold member and a hood engaging hook formed integral therewith.
8. A hood clamp comprising an elongated housing having a closed upper end and having opposite sides slotted longitudinally from the lower end thereof upwardly for a distance, a coiled spring within the housing, and an open rectangular shaped latching member connected with said housing with the lower end thereof passing across the lower end of the spring and through the slotted sides of the housing, the upper end of said latching member above the upper end of the housing being formed into a laterally bent integral finger engaging member.
9. A hood clamp comprising an elongated tubular housing having a closed upper end and having opposite sides longitudinally slotted upwardly for a distance from the lower end of the housing, a coiled spring located within the housing, and a latching member formed from a single length of flat metal having a rectangular elongated opening cut therefrom leaving spaced apart sides connected at their lower ends by a cross member, said cross member passing through the housing below the lower end of said spring and adapted to be moved upwardly through the slots in the sides of said housing, the upper end of the latching member being formed into a finger engaging handle.
10. A hood clamp containing the elements in combination defined in claim 9, said latching member also having hood engaging means extending therefrom in a direction opposite to the said handle.
11. A hood clamp comprising a supporting base, an elongated housing pivotally connected at its lower end to said base to turn about an axis perpendicular to the plane of the hood door, a coiled spring within the housing, and a latching member adapted to detachably connect with the hood door pivotally and slidably mounted on said housing and adapted to turn about an axis at its lower end substantially parallel to the plane of the hood door, and move upwardly against said spring.
12. A hood clamp comprising an elongated housing having a closed upper end and being longitudinally slotted in opposite sides from its lower end upwardly, a coiled spring located within the housing, a latching member in the form of an open rectangular

frame slidably and pivotally mounted on said housing, the lower end thereof passing through the slotted sides of the housing below the spring, hood engaging means and a finger engaging means carried by said latching member, and means on said latching member extending toward a hood door with which it is associated acting to press said door inwardly when the hood engaging means is engaged with said hood door.

13. A hood clamp comprising an elongated housing having a closed upper end and having opposite sides longitudinally slotted from the lower end of the housing upwardly, a coiled spring located within the housing, a latching member in the form of an open rectangular frame slidably and pivotally mounted on said housing, the lower end thereof passing through the slotted sides of the housing below said spring, and hood engaging means and a finger engaging means carried by said latching member adjacent its upper end, the sides of the latching member, near their lower ends being curved into substantially semi-circular form so as to extend toward a hood door with which the hood clamp is associated.

14. A hood clamp for motor vehicles which has a housing formed from a single strip of metal pressed into half round shape at portions of its length with a flat connecting portion between adjacent ends of the half round portions, said half round portions having parts of their edges removed and terminating in ears whereby when the

strip is bent at said connecting portion to bring the edges of the half round portions together, said ears are spaced apart and the open end portion of the housing is slotted at opposite sides for a distance, said slots having a width equal to the distance apart of said ears.

15. A hood clamp having a housing formed from a single strip of metal pressed into substantially half round shape at portions of its length with a flat connecting portion between the ends of the half round portions, said half round portions terminating in ears whereby when the strip is bent at said connecting portion a housing having longitudinally slotted sides is made with spaced apart ears at one end.

16. A hood clamp comprising two members, one a hollow housing having slotted sides, a spring housed within said housing, a second member formed with an elongated opening lengthwise thereof having a cross bar at one end passing through the housing through the slotted sides thereof to bear against one end of the spring, said spring at its opposite end bearing against an end of the housing, whereby said housing and slotted member may be moved lengthwise with respect to each other with a compression of said spring, a base and pivotal connections between said base and one end of one of said members.

In testimony whereof I affix my signature.

FRANK E. LIVERANCE, JR.
